[57] CLAIM

The ornamental design for a handlebar table, as shown and described.

DESCRIPTION

FIG. 1 is a top plan view of a handlebar table, showing our new design;

FIG. 2 is a front elevational view, the rear view being a mirror image thereof;

FIG. 3 is a side elevational view, the opposite side view being a mirror image thereof;

FIG. 4 is a top plan view, showing an alternative embodiment of our new design;

FIG. 5 is a front elevational view, the rear view being a mirror image thereof; and,

FIG. 6 is a side elevational view, the opposite side view being a mirror image thereof.
